UNITED STATES PATENT OFFICE

LOUISE CROSS, OF NEW YORK, N. Y., ASSIGNOR TO FRANKART, INC., OF NEW YORK,
N. Y., A CORPORATION OF NEW YORK

DESIGN FOR AN ASH TRAY OR SIMILAR ARTICLE

Application filed July 6, 1931. Serial No. 40,427. Term of patent 3½ years.

To all whom it may concern:

Be it known that LOUISE CROSS, a citizen of the United States, and resident of New York city, in the county of New York and State of New York, has invented a new, original, and ornamental Design for an Ash Tray or Similar Article, of which the following is a specification, reference being had to the accompanying drawings, forming part thereof, in which—

Fig. 1 is a perspective view of an ash tray embodying my new design; and

Fig. 2 is another perspective view thereof, viewed from another position.

I claim:

The ornamental design for an ash tray or similar article, substantially as shown.

Dated, June 27, 1931.

LOUISE CROSS.
